UNITED STATES PATENT OFFICE.

JOHN J. HAMILTON, OF ST. LOUIS, MISSOURI.

CLIP.

1,263,887.

Specification of Letters Patent. Patented Apr. 23, 1918.

Application filed February 12, 1916. Serial No. 77,921.

To all whom it may concern:

Be it known that I, JOHN J. HAMILTON, a citizen of the United States, residing at St. Louis, in the State of Missouri, have invented new and useful Improvements in Clips, of which the following is a specification.

The present invention relates to a new and useful clip adapted for securing reinforcing rods to hold them in position during the process of construction.

The primary object of the invention is to provide a simple, cheap and thoroughly effective means for holding angularly arranged rods employed in concrete construction to properly sustain the same during the process of molding.

Another object of the invention is to provide a clip for this purpose which is constructed of a single piece of wire that is centrally bowed in an angular direction to engage with one of the faces of the opposite sides of one of the reinforcing rods and which is continued longitudinally, in opposite directions, from the said bowed portion to contact with the opposite sides of the second reinforcing rod, the longitudinal portions being bent at right angles and in opposite directions beneath the said second mentioned rod and having their ends bent to engage with the sides of the rods opposite those contacted by the longitudinal portions of the clip which extend from the central bowed portion thereof, and whereby the rods will be effectively sustained in proper relation to each other and also whereby the clip may be easily and quickly secured to the rods.

With the above and other objects in view, the improvement resides in the construction, combination and arrangement of parts set forth in the following specification and falling within the scope of the appended claim.

In the drawing:

Figure 1 is a perspective view illustrating the application of the improvement,

Fig. 2 is a top plan view of the same,

Fig. 3 is a perspective view of the clip detached, and

Fig. 4 is a similar view of a modified form of the clip which may be employed upon rods which are round in cross section.

The cross bars used in concrete construction such as are indicated by the numerals 1 and 2 on the drawings must be fastened together where they cross each other so as

to be free from any movement one upon the other, as the movement of the said bars while the concrete is being poured or previous to the hardening or setting of the concrete would result in an injury and perhaps ruin to the finished work.

While various methods have been employed for holding the rods against displacement, in some instances, the said means have been found complicated, requiring time and labor in application and expense to manufacture and in other instances the devices have been found to not effectively perform their function.

My improved tie broadly indicated by the numeral 3 is formed of a single strand of wire and is consequently of a cheap construction. The strand is centrally bent upon itself to provide a loop 4, the ends of which being extended longitudinally to provide parallel legs 5—5. The loop 4 is arranged at an angle to the legs so that the legs are spaced one away from the other, but the side or arm portions of the loop preferably exert a tension toward each other and consequently tend to force the legs 5 also toward each other. The loop 4 is arranged upon the bar 1 at the point of crossing thereof with the bar 2 and is adapted to be engaged with both the outer face and with the sides of the said bar 1, while one of the legs 5 contacts with one of the sides of the bar 2 and the other leg 5 contacts with the opposite side of the said bar 2. Of course, the respective legs 5 engage with the opposite respective sides of the bar 2 which are extended in opposite directions from the sides of the bar 1. The legs 5 have their ends bent at a right angle in a line with the sides of the bar 5 as indicated by the numeral 6, and are from thence bent to provide what I will term arms and which are indicated by the numerals 7, the said arms extending transversely across the lower face of the bar 2 in opposite directions with relation to each other and the ends of these arms are bent upwardly or in the direction of the portion 6 to provide angular portions or lips 8, the said lips contacting with the sides of the bar 2 opposite that engaged by their respective arms and the portions 6 at the ends of the said arms.

In Fig. 4 the clip is substantially similar to that previously described, except that the loop 4' is round, the said clip adapted to be employed upon crossed rods which are

round in cross section and likewise the arms 7' at the ends of the legs 5' are rounded or curved in an opposite direction to that of the loop 4'.

5 With an article constructed as hereinbefore illustrated and described it will be noted that the clip may be readily positioned upon the bars as either of the legs may be swung after the looped portion of 10 said clip is arranged upon the bar 1, to bring its angular end or arm portion 7 to engage with the face of the bar 2 opposite the face of the bar 1 engaged by the loop, and the angular end 8 of what I have 15 termed the arms 7 is adapted to assist the loop 4 in forcing the legs 5 in contact with the opposite sides of the bar 2.

Having thus described the invention, what I claim is:

20 In combination with two right angularly disposed bars for concrete reinforcement, of a clip for securing such bars together, comprising a metal rod centrally bent outward

of itself to provide a loop, the connecting members for the arms of the loop being disposed at an angle, the said loop designed to straddle the rods at the crossing thereof to permit of the said connecting member of the loop resting upon the upper bar and the arms of the loop contacting with the sides of both of the bars, said rod, from the arms of the said loop, being continued longitudinally in opposite directions to rest against the opposite sides of the lower bar, and having their ends bent downwardly of the said sides of the said lower bar and extended transversely beneath the said bar and then bent upwardly to engage with the opposite sides of the said lower bar.

30 In testimony whereof I affix my signature 35 in presence of two witnesses.

JOHN J. HAMILTON.
